CARRIAGE OPENING MECHANISM

Charles B. Rosenberg, Royal Oak, Mich., assignor to Burroughs Adding Machine Company, Detroit, Mich., a corporation of Michigan

Application February 7, 1952, Serial No. 270,400

16 Claims. (Cl. 197—128)

The present invention relates generally to paper carriage operating mechanisms and more particularly to means readily attachable to existing types of business machines whereby, by a slight modification or the replacement of a single, readily accessible member and without rearranging any of the parts of such machines, the normally manually operable paper carriage mechanism thereof may be rapidly operated by power controlled from a remote point such as the keyboard of the machine.

It has been found in the past that when employing business machines such as, for example, accounting machines wherein the paper carriage throwback mechanism and the front feed mechanism are operated manually, an appreciable portion of the time required by an operator to insert and align paper and to make an entry thereon is taken up by operating these mechanisms. A substantial increase in the amount of work that such a machine could handle would be made possible if means could be provided for rapidly operating these mechanisms by power from a point remote therefrom. Various means have been suggested in the past for doing this but such means have not been generally acceptable because they require rebuilding substantial portions of the machine as well as limiting the basic versatility thereof.

One object of the present invention is to provide novel and simple means readily attachable to existing types of machines for operating the paper carriage thereof by power controlled from the keyboard of the machine.

Another object is to provide a power unit assembly arranged so as to be readily mounted in the field and without special tools upon the carriage of existing types of accounting machines and including means cooperating with the standard parts of such machines to effect selectively the various desired conditions of the paper carriage thereof by manipulating control elements disposed on the keyboard of the machine.

A more specific object is to provide an electromagnetic power assembly for mounting directly on the traveling carriage of an accounting machine and arranged to engage and cooperate with the standard parts thereof to move the paper carriage to its throwback position, to open selectively the front feed throat of the machine as an incident to the throwback movement of the carriage and automatically lock the paper carriage in its throwback position, and to close the front feed throat and release the paper carriage, all controlled from a control unit disposed at the keyboard of the machine.

A still more specific object is to provide a conversion kit for existing types of accounting machines having manually operable paper carriage throwback and front feed operating mechanisms, whereby without modifying any of the essential elements of the machine or their functions, these mechanisms may be operated by power controlled from the keyboard of the machine.

These and other objects and advantages of the present invention will be apparent from the following specification taken together with the accompanying drawings

2

wherein one embodiment is illustrated by way of example and in which:

Fig. 1 is a left-side elevational view of an accounting machine embodying the invention;

5 Fig. 2 is a perspective view of a portion of the paper carriage having the novel power throwback and front feed operating mechanism applied thereto;

Fig. 3 is a cross-sectional view taken along line 3—3 of Fig. 2;

10 Fig. 4 is a perspective view of the control switch assembly for mounting on the keyboard of the machine;

Fig. 5 is a diagram showing how the various control elements are connected in circuit with the power supply; and

Fig. 6 is a perspective view of the mechanism for operating a release switch from the motor bars.

For a better understanding of the invention it will be described as applied to the well-known "Burroughs Moon-Hopkins" billing machine of the type disclosed and described in U. S. Patent 1,336,904 to Hubert Hopkins. It will be understood, however, that the invention is applicable to various types of accounting machines having a displaceable paper carriage whether they be of the "under strike" type as illustrated or of the well-known "front strike" type.

General features

The machine illustrated is a typewriting and ten-key calculating machine wherein the typewriting section generally indicated at 10 and the calculating section generally indicated at 11 are controlled by keys 12 and 13, respectively. The calculating mechanism includes the well-known actuator racks 14 carrying type 15 in which the calculating machine type are carried. The actuator racks cooperate with a registering mechanism 16 to extend the type bars underneath and horizontally past platen 17 so that the type positioned along the printing line may be struck by printing hammers against the platen as described in the Hopkins patent referred to above. The calculating mechanism is operated by means of an electric motor 18 through a suitable clutch and drive mechanism such as, for example, disclosed in U. S. Patent 1,025,698 to Hubert Hopkins. Inasmuch as the present invention relates only to specific elements of the machine, only such portions of the machine will be described in detail as are necessary to fully appreciate the true nature of the invention.

50 The machine is provided with a conventional traveling carriage which is mounted on the machine in the usual manner by means of a pair of spaced parallel guides 21 supported on a pair of corresponding guides 20 on the machine frame by means of a suitable anti-friction arrangement such as balls 22 confined within race ways disposed in registering faces of the guides. End plates 23, of which only the left hand plate is shown in the drawings, are secured to the respective ends of the guides 21 and of the square cross shaft 24 so as to form a rigid assembly.

55 The carriage supports in the usual manner the platen assembly comprising a platen frame pivotally mounted on the carriage and supporting platen 17 as well as the equipment for holding the record or journal sheet and the individual ledger sheets or cards. The carriage and the paper holding equipment may be of the construction shown in U. S. Patent 1,774,287 to R. L. Muller to which reference is made for a more detailed description thereof. The platen frame comprises generally a pair of spaced parallel platen frame end plates 25 of which only the left hand one is shown in drawings, a cross shaft 27, and a pair of cross rods 26 which serve as means for 60 mounting the guiding bands for the journal sheets as shown in the last named Muller patent. Platen 17 is

secured to platen shaft 28 which is journaled for rotation in platen frame end plates 25, and knobs 29 are secured to the respective ends of the platen shaft for manually rotating the platen.

The platen assembly is swingably mounted on cross shaft 30 which extends between carriage end plates 23, by means of at least two spaced links 31 having the ends thereof rotatably mounted on the last mentioned cross shaft and the platen frame cross shaft 27, respectively, as better shown in Fig. 3. The usual springs 31a for permitting the carriage to be moved forwardly with respect to its normal printing position are provided. These springs are secured to respective ones of links 31 and are formed so as to engage cross shaft 32, also mounted between end plates 25, and are tensioned so as to normally position the platen assembly so that shaft 32 is held against the side of the links. Rearwardly extending lugs 33 on end plates 25 rest against a stop member 34 carried by the rear carriage guide 21, when the platen frame is in its normal printing position.

Spring member 36 is secured to cross shaft 32 and has rotatably mounted thereon the usual feed or pressure rollers 35. The pressure rollers extend through openings provided in shield 37 which is held in place by means of extensions thereof bent over carriage cross shaft 30. The platen assembly may be swung about cross shaft 30 by means of the interconnecting links 31 from the printing position illustrated in Fig. 2 wherein a forwardly extending finger 25a of end plate 25 will rest upon stud 23a depending from carriage end plate 23, to the throwback or reading position indicated in Fig. 3 wherein a roller stud 38 mounted on end plate 25 and extending to the left therefrom as viewed in Fig. 2 will rest against a stop plate 39 mounted on square shaft 24.

In many types of calculating machines now in use the platen frame is moved from the printing position to the throwback position by means of a handle attached to one or both of platen end plates 25 such as, for example, indicated by reference number 15 in Fig. 2 of U. S. Patent No. 2,055,551 to R. L. Muller, and in others the platen frame is moved by means of a linkage connecting it with a manually operable lever mounted on the front of the machine.

Mechanism for moving the platen to throwback position

In accordance with the present invention there is provided power means readily attachable to existing types of calculating machines and controlled from the keyboard of the machine for displacing the platen frame from a normal printing position such as that shown in Fig. 2 to a throwback position such as that shown in Fig. 3 independently of the cycling operation of the machine. To this end, the power unit generally indicated at 40 is rigidly mounted on the left hand carriage end plate 23 by means of threaded studs 41 extending therefrom substantially parallel to the axis of rotation of the platen frame. The power unit 40 comprises a linear solenoid 42 and a rotary solenoid 43 mounted on a common mounting plate 44. Secured to the mounting plate and extending perpendicularly therefrom for engagement with studs 41 are a pair of studs 45 whose free ends are provided with collars for engaging an inwardly extending shoulder on each of coupling nuts 46 carried by the studs for engaging the threaded ends of mounting studs 41.

Rotary solenoid 43 is mounted on plate 44 by means of a pair of threaded studs 47 extending through the plate and through spacing bushings 48 and secured in place by means of sleeve nuts as shown. The solenoid power shaft 49 extends through an opening in the plate and the axis of rotation thereof is preferably parallel with the axis of rotation of the platen frame. Solenoid 43 may be of the type generally available on the market under the trade name of "Ledex Rotary Solenoid." This type of solenoid is constructed so as to rotate the power

shaft and the lever mounted thereon through a predetermined angle, in the present example an angle of 67.5°, with an axial displacement in the order of .050". One advantage of this type of solenoid for this particular application is that the initial torque thereof is considerably greater than the torque developed during the final portion of its movement.

For the purpose of mechanically coupling the power shaft to the platen frame to raise it to throwback position when the solenoid is energized, there is provided a main power lever 50 which is securely mounted on the shaft so as to extend at substantially right angles therefrom. The power lever 50 comprises generally a cam portion 51 and a sectorial plate portion 52 extending radially in opposite directions from the shaft. The lever is mounted on the solenoid power shaft so that the cam portion thereof will just contact a sleeve or bushing 53 which is rotatably mounted on platen shaft 28 to permit rolling contact between cam portion 51 and sleeve 53 and to permit free axial movements of the solenoid power shaft. Cam portion 51 is so formed that initial rotary movement of shaft 49 will cause the platen frame to be moved forwardly a distance sufficient to enable shaft 28 to clear a printing latch 54 mounted on carriage end plate 23, and then swing the platen frame along an arc to its throwback position. The printing latch 54 is provided in order to form a positive stop for the platen frame to prevent it from moving upwardly during the printing operation.

In order to lock power lever 50 in operated position wherein it will hold the platen frame in a throwback position, there is provided latching plate 55 having a pair of spaced openings therein for receiving spacing bushings 48 on mounting studs 47. The latching plate is biased against the nuts on studs 47 by means of compression springs 56 and will tend to assume a position parallel with the mounting plate 44 and the sectorial portion 52 of lever 50. The latching plate is provided with a latching lug 57 extending outwardly from the plate and arranged so that it is normally urged against lever 50 and will engage edge 58 thereof when solenoid 43 is energized and the lever is rotated in a clockwise direction as viewed in Fig. 2.

In order to release this latch when solenoid 42 is energized and in order to open the front feed throat of the paper carriage as an incident to raising the platen frame to a throwback position, there is provided a mechanism generally indicated by reference numeral 60. This mechanism comprises a plate member or standard 61 having a yoke portion thereof straddling studs 45 and held in engagement therewith by means of recesses 62 opening towards the rear of the machine. A retaining plate or clip 62a is positioned between the legs of the yoke portion of the plate member and secured by means of a screw, for example, as shown, to the plate member in order to prevent sidewise movements thereof with respect to its support. The plate member is maintained in an upright generally vertical position by means of compression springs 63 biasing the plate against the sleeves of coupling nuts 46. An armature 64 is mounted near the upper end of the plate in juxtaposed position with respect to the magnetic yoke 65 of solenoid 42 and normally spaced a short distance therefrom. Also mounted near the upper end of member 61 but on the opposite side thereof is a roller 66 which normally is in alignment with a front feed throat opening arm 67 secured to the end of a shaft 68, and which will be engaged by the arm to cause the shaft to rotate to thereby open the front feed throat of the machine through a linkage which will be described in detail hereinafter. Shaft 68 is journaled in platen frame end plate 25 and a bracket 69 secured to the end plate and bent so that the end wherein the shaft is journaled is spaced from the end plate. Interposed between bracket 69 and the end plate 25 is a short sleeve 70 fastened to the shaft by means of set screws to permit axial adjustments of shaft

68 with respect to plate 25 in order to align arm 67 with roller 66.

When the platen frame is to be lowered from its throw-back position with open feed throat, it is important that the feed throat be completely closed to secure the newly inserted record therein prior to lowering the platen frame. To this end the invention provides means whereby the frame latch releasing mechanism is actuated as an incident to closing the front throat and will not take effect to begin to lower the frame until after the feed throat has been closed. This is accomplished by providing a frusto-conically shaped roller 71 rotatably mounted on a bracket portion 72 extending at right angles from latching plate 55 so arranged that arm 67 will engage the right hand conical surface of the roller to displace it and consequently plate 55 to the left as viewed in Fig. 2 when roller 66 is moved out of the way to the left.

Shaft 68 is operatively connected to the feed throat mechanism through a lever 75 mounted on the shaft on the opposite side of plate 25 with respect to arm 67 and carrying a roller 76 normally resting on an outwardly extending manually operable arm 77 of throat actuating lever 78. Lever 78 is secured to shaft 32 which carries the pressure rollers 35 and when outwardly extending arm 77 is depressed, it will cause lever 78 to rotate shaft 32 connected thereto thereby swinging the pressure rollers away from the platen. Lever 75 is provided with a heel portion 79 extending over the mounting bushing 80 for the front shaft 26 for preventing shaft 68 from accidentally assuming an inoperative position wherein levers 67 and 75 will extend to the left instead of to the right as viewed in Fig. 2. A tension spring 81 engaging a downwardly extending arm 82 of lever 78 biases the lever in a clockwise direction as viewed in Figs. 2 and 3 and causes rollers 35 to press against platen 17.

The control switch assembly for operating the throw-back solenoid 43 and the release solenoid 42 is shown in Fig. 4 and the manner in which it is mounted on a "Burroughs Moon-Hopkins" billing machine is indicated in Fig. 1 wherein a portion of the keyboard is shown broken away to show the position of the control switch assembly which is mounted on the right hand side of the keyboard. The control switches are enclosed within a cover 85 indicated in dotted lines in Fig. 4 mounted on a post 86, which is normally provided on the machine at the right side of the keyboard as a guide for the horizontally moving error key 87. The switch assembly comprises a supporting yoke 88 secured to post 86 between the cover and the post.

The yoke and the cover may be mounted on the standard error key post by providing a tubular, bushing-like member 98 having preferably an outside diameter equal to that of the post and having a shoulder and a reduced diameter portion extending therefrom at its upper end. The yoke and cover are provided with an opening of sufficient size to receive the reduced diameter portion of the bushing-like member which may be spun or riveted down on the top of the cover forcing the under side of the yoke against the shoulder to permanently secure together the cover, yoke and bushing-like member. The assembly may then be secured to the post 86 by means of a fastening screw 98a passing through the bushing-like member 98 and screwed into the threaded opening in the end of the post. The yoke is provided with a pair of downwardly extending ears 89 having journalled therebetween a cross shaft 90, and a pair of laterally extending ears 91 having tension springs 97 connected thereto. A pair of switch housings 92 and 93 having secured therein mercury switches 94 and 95, respectively, are pivotally mounted side by side on shaft 90 and are maintained in position thereon by means of spacing sleeves 96. The shanks of a pair of keys 100 and 101 extend through sleeves 102 of cover 85 and have the lower ends thereof slotted to receive arms 103 and 104 of housings 92 and 93, respectively. Springs 97 are connected between hous-

ings 92 and 93 and respective ones of ears 91 and normally bias the housings to the position indicated by housing 92 in Fig. 4 wherein the keys will be extended upwardly and the contacts of the switches will be open. When the keys are depressed to the position indicated by key 101 of Fig. 4, the associated switch housing will be tilted to the right to assume the position indicated by switch housing 93 and the contacts of the switch associated therewith will be closed.

In order to cause the platen frame to drop to printing position when the motor bar of the machine is actuated, there is provided an auxiliary release switch 105, Fig. 1, pivotally mounted on the frame of the machine and normally tilted to the right so as to maintain the contacts thereof in open condition. As better shown in the detailed view of the motor bar assembly in Fig. 6 as viewed from below, motor bars 106 and 107 are supported on motor bar yokes 108 and 109, respectively, rotatably mounted on motor bar cross shaft 110 journalled in the machine housing. The machine may be provided with as many as four motor bars but only two are shown in the drawing. Fixed to the cross shaft 110 is a main control member 111 connected to the machine clutch by means of a rod 112. Control member 111 is provided with a downwardly extending arm 113, of which only a portion is shown, for operating a locking slide (not shown) for interlocking the result keys in the manner described in U. S. Patent No. 1,920,477 to Robert L. Muller and illustrated in Figs. 1 and 3 thereof. Cross shaft 110 is operatively connected to the several motor bars by means of an upwardly extending arm 114 provided on each of the motor bar yokes and which carries a stud 115 adapted to engage a lever 116 fixedly mounted on the cross shaft. When one of the motor bars is depressed the cross shaft will be rocked in a clockwise sense as viewed from the left in Fig. 6 and will move the control member 111 mounted thereon to start the machine.

Control member 111 is also provided with a downwardly extending arm 117 passing through an elongated slot in the bottom plate 118 and through an aperture 119 in a slide 120. Slide 120 is slidably mounted on the under side of plate 118 by means of a stud which passes through a slot 121 in the slide and which is provided with an enlarged head 122. The slide is connected to a crank which in turn is operatively connected by means of a link 124 to a tabulator interlock (not shown) but normally located at the left side of the keyboard for preventing hand tabulation when a motor bar is depressed. A crank 125 is movable into the path of a lug 126 on slide 120 in order to prevent movement of the slide and thus lock the motor bars when the carriage is traveling following a machine operation. The motor bar mechanism so far described is normally provided in the standard type "Burroughs Moon-Hopkins" billing machine.

Auxiliary release switch 105 is detachably held in a spring clip 127 attached to an arm 128 which in turn is secured to the left hand end of a rotatable shaft 129. Shaft 129 is journalled in a pair of brackets 130 mounted on the under side of the machine by means of a pair of screws 131 (only one is shown in the drawing) which are normally provided for securing bottom plate 118 to the frame. An actuating arm 132 is secured to the other end of the shaft and is engageable by lug 126 on slide 120 when the slide is moved rearwardly by a motor bar. Arm 132 will not interfere with movements of crank 125.

It will be apparent that when one of the motor bars is depressed, arm 117 will cause slide 120 to move rearwardly and, through engagement of lug 126 with arm 132, will cause shaft 129 to be rotated in a counterclockwise direction as viewed from the left in the drawing. Such rotation of shaft 129 will cause switch 105 to be moved from the open contact position shown wherein it is tilted downwardly toward the front of the machine to its closed contact position wherein it will be tilted in the opposite direction. A spring 133 is connected between the left

hand bracket 130 and arm 128 to bias the switch assembly to the position shown.

The cycling mechanism of calculating machines is usually operated by alternating current and in order to provide D. C. operating power for solenoids 42 and 43 there is provided a full wave rectifier unit generally indicated at 140 supported by a bracket 141 mounted on the frame of the machine as indicated in Fig. 1. The rectifier unit 140 comprises four rectifiers 142 connected in a conventional bridge. A mercury switch 143 is mounted on bracket 141 in such a position that its contacts will be closed when the machine is in its normal operative position shown in Fig. 1, but will be opened when the machine is tilted backwardly for servicing. A terminal board 144 for connecting the various components of the electrical circuit together is also mounted on bracket 141.

The manner in which the various electrical components are connected in the circuit is illustrated in Fig. 5. The rectifier bridge 140 is connected to the alternating current supply through the normally closed switch 143 and the rectified voltage is applied across terminals 2 and 3 of terminal board 144. The energizing winding of solenoid 43 and a condenser 145 are connected across terminals 1 and 2 and the energizing winding of solenoid 42 is connected across terminals 2 and 4. Motor bar release switch 105 and latch release switch 94 are connected in parallel across terminals 3 and 4 and the throwback switch 95 is connected across terminals 1 and 3.

Operation

Coming now to the description of the operation of the invention, it will first be assumed that the platen frame is in the position shown in Fig. 1 and that it is desired to raise it to throwback position with the front feed throat open for replacing the record sheet.

The operator merely depresses throwback key 101 whereby switch housing 93 will be pivoted in a clockwise direction as viewed in Fig. 4 against tension spring 97. This will cause the fluid mercury in switch 95 to flow to the contact end thereof to bridge the contacts. Referring now to Fig. 5 it will be noted that closing the contacts of switch 95 will connect terminal 3 of terminal board 144 to terminal 1 to connect the output of rectifier bridge 140 across the energizing winding of solenoid 43. Solenoid 43 will operate and cause shaft 49 and hence lever 50 to rotate in a clockwise direction as viewed in Fig. 2. As it was noted above, cam 51 of lever 50 is formed so as initially to move shaft 28 and hence the platen frame attached thereto forwardly a distance sufficient to clear printing latch 54 and then upwardly along an arc of travel as defined by the cam configuration of the front edge of stop plate 39 and guided by roller 38 traveling along and in engagement with this front edge. The platen frame reaches its limiting position when roller 38 abuts the dwell or stop profile of the stop plate. By this time edge 58 of lever 50 will have cleared offset latching lug 57 of latching plate 55 and the latching lug will engage this edge to prevent the platen frame from falling back when key 101 is released and solenoid 43 is deenergized.

As the platen frame is moved to throwback position, cam 67 will engage the under side of roller 66 on the stationary upright member 61 to rotate shaft 68 and thereby cause pressure rollers 35 to be moved away from platen 17 to the position shown in Fig. 3 in a manner which will now be described. The cam 67 is so formed and positioned that as the platen is lifted, the cam will engage the under side of roller 66 to rotate shaft 68 secured thereto in a clockwise direction with respect to the platen frame until the cam reaches the position indicated in Fig. 3. The progressive tilting of cam 67 as the platen frame is lifted caused a corresponding rotation of lever 75 connected to the other end of shaft 68. Roller 76 mounted on the end of lever 75 normally just rests against arm 77 of throat controlling lever 78. As lever 75 is rotated, roller 76 will bear against arm 77 to tilt lever 78 in a counterclockwise direction against tension

spring 81. Rotation of lever 78 will cause a corresponding rotation of cross shaft 32 on which it is mounted, as well as of the spring support 36 and the pressure roller 35 also depending from this shaft. Thus, as the platen frame moves from its printing position to its throwback position, the pressure rollers 35 will be moved from a position wherein they clamp the record against the platen to a position wherein they will be separated therefrom to enable the operator to replace the record. Shield 37 is loosely held over cross shaft 30 and will follow the movements of spring member 36. The space between shield 37 and platen 17 is known in the art as the front feed throat inasmuch as the records are placed therein and removed therefrom from the front of the machine.

After the record sheet has been replaced and it is desired to drop the platen back to printing position, key 100 is momentarily depressed to close the contacts of switch 94 controlled thereby. From Fig. 5 it will be noted that when the contacts of switch 94 are closed, terminals 3 and 4 of terminal board 144 will be interconnected to connect the output of rectifier bridge 140 across the energizing windings of solenoid 42 to energize it and attract armature 64 mounted on upright member 61. This will displace roller 66 to the left, as viewed in Fig. 2 and out of engagement with cam 67. Cam 67 will therefore move against the right side of the cone-shaped camming surface of roller 71 to force it toward mounting plate 44 under the action of pressure roller biasing spring 81 through levers 78 and 75 at the same time as the pressure rolls 35 are permitted to move against the platen. The movement of roller 71 will cause latching plate 55 to tilt against the force of springs 56 to move latching lug 57 out of engagement with lever 50. The platen frame is now freed and will fall by its own weight, depressing printing latch 54 against its return spring which will cause the latch to return to the latching position shown in Fig. 2 when the platen frame reaches its printing position wherein the forwardly extending finger 25a will engage stud 23a. It will be noted that the front feed throat of the machine is closed to clamp the newly inserted record sheet in place against the platen before the platen frame is lowered.

The latching lug 57 holding the platen frame in throwback position will also be released to drop the platen frame into printing position when one of the motor bars is actuated. It will be noted from Fig. 5 that switch 105 is connected in parallel with release switch 94 and closing switch 105 will have the same effect as closing switch 94. As described above all the motor bars are operatively connected with a downwardly extending arm 117 which is connected to slide 120 so as to move the slide to the left as viewed in Fig. 1 when one of the motor bars is actuated. Thus whenever one of the motor bars is depressed, slide 120 will be caused to move to the left and thereby tilt mercury switch 105 down toward the left to close the switching contacts thereof. This in turn will energize solenoid 42 to release the platen frame if it is in its throwback position thereby permitting it to drop to printing position as explained above. Actuation of the solenoid 42 through operation of the motor bars during normal use of the machine will of course have no effect upon the normal functions of the machine.

If it is desired to raise the platen frame to view previously printed figures without opening the front throat, keys 100 and 101 are either simultaneously depressed or key 100 is first depressed and held down while key 101 is depressed. Depression of key 100 will close switch 94 and energize latch releasing solenoid 42 to attract armature 64 mounted on upright supporting member 61 and will move roller 66 to the left out of the path of cam 67. Depression of key 101 will raise the carriage to a throwback position as explained above, but as roller 66 has been moved out of the path of cam 67, this cam will engage latch releasing roller stud 71 mounted on latching plate 55 and move the plate to the left so as to maintain latching lug 57 out of engagement with lever 50.

Thus the platen frame is moved to throwback position without opening the front feed throat and without being locked in throwback position and is maintained in such throwback position only as long as the two keys 100 and 101 are depressed. As soon as the keys are released, the platen frame will drop to normal printing position.

Cut-out switch 143, shown in Fig. 1, is provided in order to open the energizing circuit for the solenoids when the machine is tilted backwardly for servicing. Backward tilting of the machine will of course cause switches 94, 95 and 105 to close due to the fact that the mercury therein will flow to the contact ends thereof, but at the same time cut-out switch 143 will open to disconnect the rectifier from the A. C. power supply. The cut-out switch is mounted so as to remain closed in normal operating positions of the machine wherein switches 94, 95 and 105 will be open.

Condenser 145 is permanently connected across solenoid 43 in order to stabilize the operation thereof but no condenser is needed for the less powerful solenoid 42.

An important feature of the present invention resides in the fact that the various component parts thereof may readily be mounted on existing types of calculating machines or typewriting machines generally and particularly the "Burroughs Moon-Hopkins" billing machine referred to above and which has been illustrated in the drawings. The only part in this latter type of calculating machine which has to be modified is the platen frame stop member designated with reference numeral 18 in Fig. 4 of the above mentioned U. S. Patent No. 2,055,551 to R. L. Muller. This stop member has in the past been used for the dual purpose of limiting the throw of the platen frame as well as maintaining it in throwback position. When used with the present invention, the stop member 39 is formed so as to merely act as a stop for limiting the backward movement of the frame but will not prevent it from falling down to printing position by its own weight when the latching mechanism is released by energizing solenoid 42 as explained above. It may be preferable to provide a second stop member 39 on the right hand side of the carriage in order to stabilize both ends of the frame. By properly forming the front cam surfaces of these stop members, the frame member will be positively guided throughout its entire movement between throwback and printing positions through engagement of roller studs 38 with the cam edges.

The machine may, if desired, readily be arranged to control the carriage opening mechanism by the carriage itself. Thus throwback switch 95 or a switch similarly connected in the circuit may be mounted on the carriage or on the frame of the machine so as to be actuated to open the carriage automatically when the carriage moves into a preselected columnar position.

The mounting ear 99 extending from the rear of the control box cover 85 may be fastened to the right hand side of the machine by means of a mounting screw passing through a mounting hole located in the side panels of the typewriter case portion of the machine and secured by a nut.

Arm 77 of pressure roller controlling lever 78 may be manually depressed in order to adjust the work sheet on rare occasions when this is necessary or when installing a new journal.

Bracket 69 may conveniently be mounted on plate 25 by screws passing through holes provided in the plate for mounting the old hand throwback lever usually provided in the "Burroughs Moon-Hopkins" type billing machine referred to above.

Although mercury switches were used in the above described preferred embodiment of the invention because of their long life and dependable operation, it will be evident to those skilled in the art that other types of switches, whether they are gravity operated or not, may be used in their place if the actuating mechanism therefor are properly redesigned.

I claim:

1. A machine of the class described having a movable carriage, a platen frame pivotally mounted on said carriage and movable between a printing position and a throwback position, a front feed throat operating mechanism, electromagnetic means mounted on said carriage, means for coupling said electromagnetic means to said frame to move said frame from said printing position to said throwback position when actuated, manually operable switching means for connecting said electromagnetic means in circuit with a source of energization, means responsive to movements of said platen frame to actuate said front feed throat operating mechanism as an incident to such movements and means selectively operable to disable said actuating means for said feed throat operating mechanism to permit said platen frame to be moved to its throwback position with said throat in normal condition.
2. In a machine of the class described having a movable carriage, and a platen frame mounted on said carriage movable from a printing position to a throwback position, first electromagnetic means coupled to said platen frame and adapted, when energized, to move said platen frame from said printing position to said throwback position, latching means automatically latching said platen frame in throwback position, second electromagnetic means operatively connected to said latching means and adapted, when energized, to release said latching means to permit said platen frame to assume normal printing position, and first and second switching means actuated from the keyboard of the machine for selectively connecting said first and second electromagnetic means respectively, to a source of energization.
3. In a machine of the class described having a movable carriage, and a platen frame mounted on said carriage and movable between a printing position and a throwback position, electromagnetic means mounted on said carriage coupled to said platen frame and adapted, when energized, to move said platen frame from said printing position to said throwback position, latching means automatically locking said platen in the throwback position, second electromagnetic means mounted on said carriage and coupled to said latching means and adapted, when energized, to release said latching means to permit said carriage to fall to its printing position by its own weight, switching means for connecting said first named electromagnetic means in circuit with a source of energization, and second switching means for connecting said second electromagnetic means in circuit with a source of energization.
4. In a machine of the class described having a platen frame movable between a printing position and a throwback position, and a record-receiving feed throat movable between a closed-throat and open-throat condition, means for opening said feed throat as an incident to throwback movement of said platen frame comprising an actuating arm pivotally mounted on said frame, means coupling said arm and said feed throat to cause said feed throat to open in response to pivotal movement of said arm with respect to said frame, arm engaging means mounted on said machine and disposed in the path of said arm as said platen frame is moved from printing to throwback position to cause said arm to rotate with respect to said platen frame to open said feed throat and means operably connected to said arm engaging means for selectively moving said arm engaging means out of the path of said arm to permit movement of said platen frame to throwback position with said feed throat remaining closed.
5. In a machine of the class described having a travelling carriage, a platen frame movable between a printing position and a throwback position, and a record-receiving feed throat on said platen frame movable between a closed-throat and an open-throat condition, an actuating arm pivotally mounted on said platen frame, means coupling said arm with said feed throat to cause said throat to open in response to pivotal movement of said arm with

respect to said frame, arm engaging means mounted on said carriage and disposed in the path of said arm as the platen frame is moved from its printing position to its throwback position to cause said arm to rotate with respect to said platen frame to open said feed throat, and means for selectively displacing said arm engaging means out of the path of said arm.

6. In a machine of the class described having a travelling carriage and a platen frame mounted on said carriage for movement between a printing position and a throwback position, power means coupled to said platen frame and adapted, when energized, to displace said platen frame from its printing position to its throwback position, means for automatically latching said platen frame in said throwback position, latch releasing means, front-feed means movable from closed-throat to open-throat condition and vice-versa, resilient means operatively connected to said front-feed means to urge said front-feed means toward closed-throat condition, means operatively connected with said front-feed means and effective to cause said front-feed means to assume its open-throat condition against the force of said resilient means as an incident to the throwback movement of said platen frame, power means coupled to said front-feed throat-opening means and adapted, when energized, to render said front-feed throat-opening means ineffective, and means arranged for engagement with said latch releasing means and movable with throat movements of said front-feed means to engage said latch releasing means to release said platen frame latching means as an incident to the throat-closing movement of said front-feed means effectuated by said resilient means.

7. In a machine of the class described having a platen frame movable between a printing position and a throwback position, power means coupled to said platen frame and operable independently of a machine cycle to move said platen frame from said printing position to said throwback position, latching means automatically latching said platen frame in its throwback position, front-feed means for receiving and holding a work sheet in front-feed position, said front-feed means being movable from closed to open throat condition and vice versa, resilient means for biasing said front-feed means toward closed-throat condition, an arm pivotally mounted on said platen frame and coupled to said front-feed means to control throat movements thereof, an arm reaction element engageable by said arm upon movement of said platen frame from printing position to throwback position to pivot said arm and open said throat as an incident to such movement of said frame, power means operable, when energized, to disengage said arm reaction element from said arm, and latch releasing means engageable by said arm upon said arm being disengaged from said arm reaction element and caused to rotate under the influence of said resilient means urging said front-feed means to a closed-throat condition.

8. A machine of the class described having a travelling carriage; a platen frame mounted on said carriage for movements between a printing position and a throwback position, power means functioning independently of the cycling operation of the machine and coupled to said platen frame to move said platen frame from printing position to throwback position when energized, latching means automatically locking said platen frame in throw-back position, front-feed means having a feed throat movable between a closed throat and open throat condition, resilient means for normally biasing said front-feed means toward closed throat condition, mechanism including a rotatable actuating shaft to operate said front-feed means, an arm mounted on said shaft for rotation therewith, a standard mounted on said carriage, arm engaging means mounted on said standard and arranged to be engaged by said arm to cause said shaft to be rotated so as to open said feed throat against the biasing force of said resilient means upon said platen frame being moved to its throwback position, latch releasing means including an actuating por-

tion arranged in the path of said arm but normally prevented from engagement therewith by said arm engaging means interposed therebetween, and means for selectively displacing said arm engaging member to permit said arm, 5 when the platen frame is in throwback position, to be moved under the influence of said throat closing biasing means to engage said actuating portion of said latch releasing means to release said latching means as an incident to closing said front feed throat thereby permitting said platen frame to fall down by its own weight to its printing position after said feed throat has been closed.

9. A machine of the class described comprising a travelling carriage, a platen frame mounted on said carriage for movements between a printing position and a throwback position, a rotary solenoid having high initial torque mounted on said carriage and arranged to operate independently of the cycling operation of the machine, lever means for coupling said solenoid to said platen frame to move said platen frame from printing position to throwback position upon said solenoid being energized, means for selectively energizing said solenoid from the keyboard of the machine, latching means automatically locking said platen frame in throw-back position, front-feed means having a feed throat movable between a closed throat and open throat condition, a biasing spring for normally urging said front-feed means toward closed-throat condition, mechanism including a rotatable actuating shaft to operate said front-feed means and a throat operating arm mounted on said shaft for rotation therewith, a standard mounted on said carriage, arm engaging means mounted on said standard and arranged to be engaged by said arm to cause said shaft to be rotated so as to open said feed throat against the biasing force of said spring during the throwback movement of said platen frame, latch releasing means including an actuating portion arranged in the path of said arm but normally prevented from engagement therewith by said arm engaging means interposed therebetween, a linear solenoid mounted on said carriage, an armature for said linear solenoid mounted on said standard for displacing said standard and said arm engaging means mounted thereon, when said linear solenoid is energized to permit said arm, when the platen frame is in throwback position, to be moved under the influence of said throat closing biasing spring to engage said actuating portion of said latch releasing means to release said latching means as an incident to closing said front feed throat thereby permitting said platen frame to fall down by its own weight to its printing position, and means for selectively energizing said linear solenoid from the keyboard of the machine.

10. A kit for readily modifying an accounting machine of the type including a platen pivotally mounted on a travelling carriage and having a manually operable platen throwback mechanism and a throat operating mechanism, so that these mechanisms may be operated by power controlled from the keyboard of the machine, comprising a power unit readily attachable to the carriage and including power means for engaging the platen frame and adapted, when energized, to cause said platen frame to be raised to throwback position, latching means for latching said platen frame in said throwback position, latch releasing means, mechanism for cooperating with the existing manually operable throat controlling lever of the throat operating mechanism and adapted to depress said lever to open said feed throat as an incident to the throwback movement of said platen frame, second power means operatively connected to said lever, depressing mechanism and adapted, when energized, to render said last named mechanism ineffective to control said lever, and means responsive to the closing movement of the front feed throat, when the platen frame is in latched throwback position, to actuate said latch releasing means, a switching unit for mounting on the keyboard of the machine comprising a first and a second switching means connected in the energizing

13

circuit of said first and said second power means of said power unit, and manually operable keys for selectively operating said first and second switching means; a power supply unit including rectifying means connected in circuit with said first and second power means and the switching means therefor and adapted to be attached as a unit to the machine; and cam means for limiting the throwback movement of the platen frame without retaining it in throwback position to replace existing cam means of the machine normally adapted to limit the throwback movement of the machine as well as to retain it in throwback position.

11. A kit according to claim 10 which further comprises auxiliary switching means for mounting on the machine and including means for mechanically connecting said switching means to the motor bar of the machine to close upon said motor bar being actuated, and means for electrically connecting said auxiliary switch in shunt with said second switching means.

12. A kit according to claim 11 in which said switching means comprise pivotally mounted mercury switches and which further comprises servicing lockout switching means comprising a mercury switch connected in the main energizing circuit and included in said power supply unit and mounted so as to be normally closed when said machine is in normal operating position and to be opened to deenergize the power supply circuit when said machine is tilted, for servicing, to a position wherein one of said other switching means will become closed.

13. In a machine of the class described having a movable carriage and a platen frame mounted on said carriage for movement between an operating position and a throwback position, electrically operated actuating means mounted on said carriage, means for coupling said actuating means with said platen frame to said platen frame to throwback position upon said actuating means being energized, switching means for connecting said actuating means in circuit with a source of electrical energy, latching means automatically latching said platen frame in throwback position, and means for selectively rendering said latching means ineffective during throwback operations of said platen frame whereby said platen frame will remain in throwback position only as long as said switching means is closed.

14. In a machine of the class described having a movable carriage, a platen frame mounted on said carriage for movement between a printing position and a throwback position, and a feed throat movable between a closed-throat and open-throat condition, electrically operated actuating means mounted on said carriage and coupled to said platen frame and adapted, when energized, to move said platen frame from said print-

14

ing position to said throwback position, switching means for connecting said platen frame actuating means in circuit with a source of electrical energy, throat actuating means to open said throat as an incident to throwback movement of said platen frame and to close said throat as an incident to return movement of said platen frame, latching means automatically latching said platen frame in throwback position, and means for selectively rendering said throat actuating mechanism and said latching mechanism ineffective during throwback operation of said platen frame whereby said platen frame will remain in throwback position only as long as said switching means is closed and whereby said feed throat will remain closed during said throwback operation of said platen frame.

15. In a machine of the class having a movable carriage and a platen frame mounted on said carriage movable between a printing position and a throwback position, releasable latching means for locking said platen frame in throwback position, power means mounted on said carriage and operatively coupled to said platen frame and adapted, when energized, to move said platen frame from said printing position to said throwback position, power means connected to said latching means operable, when energized, to disable said latching means, and means for connecting operating power to said first and last named power means including means for selectively controlling the flow of operating power to said power means for moving the platen frame and said power means for disabling said latching means.

16. In a machine of the class having a movable carriage and a platen frame mounted on said carriage movable between a printing position and a throwback position, electromagnetic means of the rotary type having high initial and relatively low final torque mounted on said carriage for rotary movements of its output member about an axis substantially parallel with the direction of movement of said carriage and operatively coupled to said platen frame and adapted, when energized, to move said platen frame from said printing position to said throwback position, and manually operable switching means for connecting said electromagnetic means in circuit with a source of energization.
